UNITED STATES PATENT OFFICE.

MADELEINE M. MILLS, OF NEW YORK, N. Y.

DESIGN FOR A CORSET.

SPECIFICATION forming part of Design No. 31,292, dated July 25, 1899.

Application filed June 22, 1899. Serial No. 721,489. Term of patent 7 years.

To all whom it may concern:

Be it known that I, MADELEINE M. MILLS, a citizen of the United States, and a resident of the city, county, and State of New York, have invented and produced a new, useful, and original Design for an Article of Manufacture—namely, Corsets—of which the following is a specification, reference being had to the accompanying drawing, forming a part thereof.

In the said drawing the figure shows the corset as seen from the front.

The leading feature of my design consists in a corset the upper edge of which has the shape or configuration substantially as shown.

A A represent the two sides of the corset, which meet along the median vertical line y y. The waist is indicated by the horizontal line x x. The upper-edge contour of the

front of the corset consists of two margins ²⁰ a a, which diverge from a point z on the median line near the waist-line and extend upwardly and outwardly to the points c c, respectively. The contour of the upper edge of the back of the corset consists of the substantially horizontal margin d at the middle ²⁵ and the upwardly-inclined margins e e.

What I claim is—

The design for a corset substantially as herein shown and described.

In witness whereof I have hereunto signed my name, this 19th day of June, 1899, in the presence of two subscribing witnesses.

MADELEINE M. MILLS.

Witnesses:

PETER A. ROSS,
HENRY CONNETT.
